MOISTENING MEANS FOR DUPLICATING MACHINES

Robert F. Morrison, Oak Park, Ill., assignor to
Ditto, Incorporated, Chicago, Ill., a corpora-
tion of West Virginia

Application May 24, 1937, Serial No. 144,430

11 Claims. (Cl. 91—67.8)

The invention relates to moistening means for duplicating machines and is particularly adapted to be embodied in a duplicating machine of the type wherein master sheets of paper are mounted upon a printing or duplicating drum and data written or typewritten upon the master sheets is duplicated on copy sheets which are moistened with a solvent for the ink on the master sheet, the moistened surfaces of the copy sheets being brought into contact with the master sheet.

10 The improved moistening means preferably comprises feed rollers which feed the copy sheets to the duplicating drum. Solvent is supplied to one of the feed rollers and it moistens the copy sheets with the solvent as it co-operates with the other roller to advance the copy sheets to the duplicating drum. The moistening roller is preferably substantially non-absorbent but the co-operating roller is preferably absorbent so that a 15 quantity of solvent will not collect at the bight of the rollers. In the preferred form of the invention, the absorbent roller has an outer covering of felt impregnated with latex, which covering absorbs excess moisture at the bight between the rollers.

25 Other objects and advantages of the invention will presently appear, reference being had to the following description, wherein—

Fig. 1 is a fragmentary longitudinal vertical section taken through a duplicating machine provided with moistening means which embodies the invention.

Fig. 2 is a fragmentary section taken on line 2—2 of Fig. 1.

30 Fig. 3 is an enlarged section taken on line 3—3 of Fig. 2.

Fig. 4 is a fragmentary elevation, partly in section, of feeding rollers which embody another form of the invention.

40 Fig. 5 is a section taken on line 5—5 of Fig. 4.

Fig. 6 is a fragmentary elevation, partly in section, of feeding rollers which embody another form of the invention.

45 Fig. 7 is a section taken on line 7—7 of Fig. 6.

Fig. 8 is a fragmentary elevation, partly in section, of feed rollers which embody another form of the invention.

50 Fig. 9 is a section taken on line 9—9 of Fig. 8.

Fig. 10 is a fragmentary elevation, partly in section, of feed rollers which embody another form of the invention.

Fig. 11 is a section taken on line 11—11 of Fig. 10.

55 Fig. 12 is a fragmentary elevation, partly in

section, of a feed roller which embodies another form of the invention.

Fig. 13 is a fragmentary elevation, partly in section, of a feed roller which embodies still another form of the invention, and

Fig. 14 is a fragmentary elevation, partly in section, of a feed roller which embodies still another form of the invention.

Referring for the present to Figs. 1 to 3, inclusive, which embody a preferred form of the 10 invention, the reference character 20 designates the frame of a duplicating machine of a well known type. Journaled on a shaft 21 mounted in the frame 20 is a duplicating drum 22 provided with means (not shown) whereby a sheet of paper 15 may be clamped to the drum. Disposed beneath and in engagement with the cylindrical surface of the drum 22 is a platen roller 23 mounted on a shaft 24 journaled in ball bearings 25 which are carried by levers 36a pivoted upon pins 37a 20 projecting from the frame 20.

Briefly, the functions of the duplicating drum 22 and the platen roller 23 are this: A master sheet is first obtained by typing or writing upon a sheet of paper with a carbon sheet contacting 25 the back surface thereof. The typing or writing appears in reverse on the back side of the sheet. This sheet, called the master sheet, is then clamped to the duplicating drum which is then rotated. The copies are obtained by advancing 30 copy sheets between the drum 22 and the platen roller 23 so that each copy sheet is brought into contact with the data on the master sheet. The copy sheets are moistened, preferably, on one side with a solvent for the ink or carbon on the master sheet before they are brought into contact with the master sheet. As is well known to those skilled in the art, a relatively large number of copies may be made by practicing this method.

The means for feeding the copy sheets to the 40 duplicating drum 22 and the platen roller 23 preferably comprises co-operating feeding and moistening rollers 30 and 31 disposed in the frame 20 so that when they are rotated in the proper directions they will advance the copy 45 sheets between them to the bight of the duplicating drum 22 and the platen roller 23. The roller 30 is adapted to apply the solvent to the copy sheets, the solvent being supplied preferably to the roller 30 by a strip of felt 34, or the equivalent, which contacts the cylindrical surface of the roller 30. The strip of felt 34 is secured to a container 35 to which solvent is delivered through a tube 36, the solvent being obtained from a reservoir or receptacle 37 and fed to the 50 55

tube 36 by any suitable means (not shown). Projecting from the container 35 is a strip of felt 38 which contacts the strip 34, the construction being such that the solvent in the container 35 passes through the strip 38 into the strip 34 and is applied by the strip 34 to the roller 30.

The roller 30 is preferably mounted on a shaft 40 journaled in the frame 20 (Fig. 2). The roller 30 is preferably formed of a plastic material 10 comprising resinated rubber and fillers which act as colloidal agents in the rubber. This composition is sold under the trade name of "Roulene." However, the details of the material from which the roller 30 is formed do not form 15 a part of this invention. As stated above, the roller 30 preferably comprises non-absorbent material and has a smooth, relatively hard outer surface.

The roller 31 is mounted upon a shaft 41 which 20 has its ends journaled in sleeves 43 removably mounted in the free ends of levers 44 which are pivoted to the frame 20 by pins 45. Pivoted to the free ends of the levers 44 are links 47 and 48 which are provided with slots 49 at their lower 25 ends. Pins 50 projecting from the frame 20 ride in the slots 49, the construction being such that the levers 44 may be displaced angularly in a clockwise direction (Fig. 1) against the action of a spring 52 which has one end secured to a pin 30 53 projecting from the frame 20 and has its other end secured to one of a plurality of teeth 55 of a plate 56 secured to the lower end of the link 48. Obviously, the spring 52 urges the roller 31 into 35 engagement with the roller 30. The pressure exerted by the roller 31 upon the roller 30 may be varied by hooking the lower end of the spring 52 to a selected one of the teeth 55. It will be understood that the free ends of the levers 44 may be lowered against the action of the spring 52 so 40 that the roller 31, the shaft 41 and the sleeves 43 may be lifted from the free ends of the levers if it is desired to clean or replace the roller 31. Means is provided for lowering the free ends of the levers 44. This means preferably comprises 45 a pin 44a projecting from a shaft 44b journaled in the frame 20. The shaft 44b may be displaced angularly in a clockwise direction (Fig. 1) to have the pin 44a engage a pin 44c projecting from the link 48. The displacement of the shaft 44b 50 may be continued until the pin 44a has lowered the pin 44c and the link 48 a sufficient distance to permit removal of the roller 31.

The roller 31 preferably comprises a cylindrical center or roller 60 formed from solid resilient rubber, the center 60 being provided with a covering 61 on its cylindrical surface. The covering 61 preferably comprises felt impregnated with latex, the latex being impregnated with one of the preservatives usually employed for this purpose. 60 The felt is impregnated preferably with the latex by dipping it into the latex and alternately compressing and releasing it while it is in the latex, or the latex may be brushed or sprayed on the felt. The strip of felt is then permitted to dry, where- 65 upon the latex dries in such manner that it has a large number of relatively minute pores or openings in it. The dry felt impregnated with latex is then secured to the center 60. However, in some instances, it may be desirable to impregnate the felt after it has been applied to the center 60 or to apply the impregnated felt to the center 60 before it has dried. In practice, it has been found that the covering 61 will absorb quickly and efficiently any solvent which tends to collect be- 70 tween the rollers 30 and 31. This prevents rela-

tively large quantities from being deposited from time to time on the leading ends of copy sheets being advanced between the rollers 30 and 31.

Secured to the drum 22 at one end thereof is a gear 70 which meshes with a pinion 71 journaled by a pin 72 projecting from the frame 20. The pinion 71 meshes with a pinion 73 with which the shaft 40 is constrained to rotate. Obviously, when the drum 22 is rotated in a counter-clockwise direction (Fig. 1), the roller 30 will rotate 10 in a counter-clockwise direction and will cause the roller 31 to rotate in a clockwise direction to advance copy sheets from a table 75 to the duplicating drum 22 and the pressure or platen roller 23. The table 25 is mounted in the frame 20. 15

The operation of the above described apparatus is substantially as follows: After a master sheet has been secured to the drum 22, a stack of copy sheets may be placed upon the table 75 and advanced one by one to the feed rollers 30 and 31. 20 Of course, the duplicating drum is being rotated at this time so that the rollers 30 and 31 will advance each copy sheet in turn to a point where the leading edge of each copy sheet will be drawn between the duplicating drum 22 and the pressure or platen roller 23 to press the copy sheet against the master sheet. As the copy sheets pass between the rollers 30 and 31, their upper surfaces are provided with a film of solvent, as described above, and when this solvent contacts the 25 data on the master sheet, the ink or carbon will be dissolved sufficiently to duplicate the data on the copy sheets.

In the preferred form of the invention, the center or core 60 is preferably ground to have a 30 substantially perfect cylindrical surface. Then after the cover 61 has been applied thereto, the roller is ground again so that its outer cylindrical surface will be substantially perfect and concentric with the axis of rotation of the shaft 41. It 40 may also be mentioned that the outer cylindrical surface of the roller 30 is also preferably ground so that it is concentric with the axis of rotation of the shaft 40.

Referring now to Figs. 4 and 5 wherein another embodiment of the invention is illustrated, reference characters 30a and 31a designate rollers which may be substituted for the rollers 30 and 31, respectively, described above.

The roller 30a is preferably identical in construction with the roller 30. The roller 31a is mounted upon a shaft 41a and comprises a center or core 60a formed of resilient rubber. The cylindrical surface of the core 60a is provided with a plurality of annular grooves 100 and is 55 provided with a covering 61a which is preferably formed by mixing sponge rubber with small pieces of cork, the mixture being rolled into sheets before it is applied to the core 60a. The covering or coating 61a is sufficiently porous to enable it 60 to absorb solvent collecting between the rollers 30a and 31a. It is understood, of course, that the rollers 30a and 31a have the same functions as the rollers 30 and 31, respectively, and the cylindrical surfaces thereof are also preferably ground so as to have them concentric with the axes of rotation of their respective shafts. The shaft for the roller 30a is shown at 40a.

The grooves 100 assist the covering 61a to prevent the accumulation of solvent between the rollers 30a and 31a as the covering 61a may become relatively saturated and a portion of the solvent may evaporate into the grooves 100.

The cover 61a is relatively absorbent and will 75

prevent a large accumulation of solvent at the bight of the rollers 30a and 31a.

In Figs. 6 and 7 another form of the invention is illustrated. Feeding rollers 30b and 31b, respectively, described above and are mounted on shafts 40b and 41b, respectively, which may be utilized instead of the shafts 40 and 41, respectively. The roller 30b is preferably identical with the roller 30 described above. The roller 31b preferably comprises a core 60b formed of ceramic material, the outer cylindrical surface of the core being preferably ground so that it will be concentric with the axis of rotation of the shaft 41b. The covering 61b is mounted on the cylindrical surface of the core 60b and is preferably made of the same material as the covering 61 described above so that it will absorb solvent collecting between the rollers 30b and 31b. The outer surface of the covering 61b is preferably ground so that it will be concentric with the axis of rotation of the shaft 41b. It will be noted that the felt covering 61b is in the form of a sleeve and that the ends of the covering are brought down over the ends of the core 60b and clamped to the shaft 41b by rings 101. Only one end of the shaft 41b is shown but it will be understood readily that the same construction is employed on both ends for securing the covering 61b to the shaft.

Still another form of the invention is illustrated in Figs. 8 and 9 wherein the reference characters 30c and 31c designate rollers which may be substituted for the rollers 30 and 31, respectively. The rollers 30c and 31c are mounted on shafts 40c and 41c, respectively, which may replace the shafts 40 and 41, respectively. The roller 30c is preferably identical in construction with the roller 30 described above. The roller 31c comprises a tubular core 60c mounted on the shaft 41c, the core 60c being preferably formed of resilient rubber. The core 60c is provided with a plurality of annular grooves 105 which have the same function as the annular grooves 100 described above. The outer cylindrical surface of the core 60c is preferably ground to have it concentric with the axis of rotation of the shaft 41c. The core 60c is provided with a covering 61c which is preferably made from the same material as the covering 61 described in connection with Figures 1 to 3, inclusive. This material is felt treated with latex as described above. The rollers 30c and 31c will cooperate to advance copy sheets to the duplicating drum 22 and the pressure or platen roller 23.

A further form of the invention is shown in Figs. 10 and 11 wherein the reference characters 30d and 31d designate rollers which may be substituted for the rollers 30 and 31, respectively, the roller 30d being preferably identical in construction with the roller 30 described above and being mounted on a shaft 40d which corresponds to the shaft 40 described above. The roller 31d is mounted on a shaft 41d adapted to be substituted for the shaft 41. The roller 31d comprises a tubular core 60d mounted on the shaft 41d and preferably formed of resilient rubber. The outer cylindrical surface of the core 60d is provided with grooves or slots 106 extending longitudinally of the core. The outer cylindrical surface of the core 60d is preferably ground to have it concentric with the axis of rotation of the shaft 41d. Displaced around the core 60d is a covering 61d of felt impregnated with latex, the covering of the material 61d being

preferably the same as that of the covering 61 described in connection with Figs. 1 to 3, inclusive. The function of the grooves or slots 106 is the same as that of the grooves 100.

In Fig. 12, the reference character 31e designates a roller which may be substituted for the roller 31 described above, the roller 31e being mounted on a shaft 41e corresponding to the shaft 41. The roller 31e comprises a core 60e of resilient rubber mounted upon the shaft 41e. The outer cylindrical surface of the core 60e is provided with a groove 107 extending helically around the core. The outer surface of the core 60e is preferably ground to have it concentric with the axis of rotation of the shaft 41e. The core 60e is provided with a covering 61e which is preferably identical with the covering 61 described in connection with Figs. 1 to 3, inclusive.

Fig. 13 discloses another form of the invention. A roller 31f is mounted upon a shaft 41f and may be substituted for the roller 31 described above. The roller 31f comprises a core 60f mounted on the shaft 41f and preferably formed of resilient rubber. The outer cylindrical surface of the core 60f is provided with a plurality of annular grooves 110 which are filled with absorbent material 109 such as felt or fabric. The outer cylindrical surface of the core 60f is preferably ground to have it concentric with the axis of rotation of the shaft 41f. A cover 61f disposed around the core 60f is preferably formed of felt treated with latex in the manner described in connection with the covering or sleeve 61 shown in Figs. 1 to 3, inclusive. The absorbent material 109 is adapted to absorb solvent from the covering 61f.

Fig. 14 shows a roller 31g which may be substituted for the roller 31, described above, and is mounted on a shaft 41g corresponding to the shaft 41. The roller 31g comprises collars 111 secured to the shaft 41g by set screws 112. As only one end of the shaft 41g is shown, only one of the collars 111 appears in the drawings. Interposed between the collars 111 and disposed around the shaft 41g are a plurality of discs 113 which are preferably formed from resilient rubber, the discs 113 being spaced from each other by intermediate discs 114 of some material such as felt or fabric that will absorb the solvent. It will be noted that the end surfaces of the discs 113 and 114 are not at right angles to the axis of rotation of the shaft 41g. Disposed around the discs 113 and 114 and the collars 112 is a tubular covering 61g which is preferably identical with the covering 61 described above in connection with Figs. 1 to 3, inclusive. The collars 111 and the discs 113 and 114 co-operate to form a core 60g which corresponds to the core 60 of the roller 31. Preferably, the outer cylindrical surface of the core 60g is ground to have it concentric with the axis of rotation of the shaft 41g and the covering 61g is also preferably ground to have its outer surface concentric with the axis of rotation of the shaft 41g. As indicated, it is preferable, in each instance, to have the absorbent covers of the rollers 31, 31a, 31b, 31c, 31d, 31e, 31f and 31g ground to have them concentric with their respective shafts.

It may be mentioned that in practice it has been found that the above described rollers comprising outer coverings of felt impregnated with latex are exceedingly advantageous as there appears to be a relatively high co-efficient of friction between latex and paper so that the copy sheets are fed accurately in each instance and perfect registry is obtained with the impression 75

carried by the master sheet. Also, as indicated above, the latex is porous when dried and this characteristic causes it to aid in removing excess solvent from the solvent applying roller.

5 While I have shown and described certain embodiments of my invention, it is to be understood that it is capable of many modifications. Changes, therefore, in the construction and arrangement may be made without departing from 10 the spirit and scope of the invention as disclosed in the appended claims, in which it is my intention to claim all novelty inherent in my invention as broadly as permissible, in view of the prior art.

I claim:

15 1. In a roller for pressing a copy sheet against a cooperating driven roller to which solvent is delivered for application to a copy sheet passing between the rollers, the combination of a supporting shaft, and a facing of fibrous material 20 on said shaft impregnated with latex and having its outer surface in the form of a cylinder in concentric position on the shaft.

2. In a roller for pressing a copy sheet against a cooperating driven roller to which solvent is 25 delivered for application to a copy sheet passing between the rollers, the combination of a supporting shaft, and a facing of felt on said shaft impregnated with latex and dried into porous form with its outer surface normally cylindrical 30 in concentric position on the shaft.

3. In a roller for pressing a copy sheet against a cooperating driven roller to which solvent is delivered for application to a copy sheet passing 35 between the rollers, the combination of a supporting shaft, and a facing of fibrous material on said shaft impregnated with an aqueous dispersion of rubber adapted upon drying to cause the facing to remain porous and absorbent and having its outer surface in the form of a cylinder in concentric position on the shaft.

4. In a roller for pressing a copy sheet against a cooperating driven roller to which solvent is delivered for application to a copy sheet passing between the rollers, the combination of a supporting shaft, a core of rubber in the form of a cylinder on said shaft, and a facing of felt on said core 45 impregnated with a rubber dispersion adapted upon drying to cause the felt to remain porous and absorbent and having its outer surface in the form of a cylinder in concentric position on the shaft.

5. In a roller for pressing a copy sheet against a cooperating driven roller to which solvent is delivered for application to a copy sheet passing 50 between the rollers, the combination of a supporting shaft, and an absorbent facing on said shaft

of felted fibrous material impregnated with an aqueous rubber dispersion and having its outer surface ground into the form of a cylinder in concentric position on the shaft.

6. In a roller for pressing a copy sheet against 5 a cooperating driven roller to which solvent is delivered for application to a copy sheet passing between the rollers, the combination of a supporting shaft, and a facing of absorbent material on said shaft and impregnated with latex for making 10 its outer surface porous.

7. In a roller for pressing a copy sheet against a cooperating driven roller to which solvent is delivered for application to a copy sheet passing 15 between the rollers, the combination of a core member in the form of a cylinder having depressions in its cylindrical surface, and a comparatively thin facing of felt impregnated with latex secured on said core about said depressions.

8. In a roller for pressing a copy sheet against a cooperating driven roller to which solvent is delivered for application to a copy sheet passing 20 between the rollers, the combination of a core member in the form of a cylinder having depressions in its cylindrical surface, absorbent means 25 in said depressions, and a facing of felt impregnated with latex secured on said core about said depressions.

9. In a roller for pressing a copy sheet against a cooperating roller to which solvent is delivered for application to a copy sheet passing between 30 the rollers, the combination of a core member in the form of a cylinder, the surface of said cylinder comprising alternate portions of rubber and 35 of moisture absorbent material, and a facing of felt impregnated with latex secured on said core overlying said surface.

10. In a roller for pressing a copy sheet against a cooperating roller to which solvent is delivered for application to a copy sheet passing between 40 the rollers, the combination of a supporting shaft, a core of ceramic material in the form of a cylinder on said shaft, and a facing of felt on said core impregnated with latex.

11. In a roller for pressing a copy sheet against a cooperating driven roller to which solvent is delivered for application to a copy sheet passing between the rollers, the combination of a core member in the form of a cylinder having depressions in its cylindrical surface, and a comparatively thin facing of felt impregnated with latex secured on said core about said depressions, said depressions being in the form of grooves disposed substantially circumferentially of said cylinder.

ROBERT F. MORRISON. 55
